UNITED STATES PATENT OFFICE.

HARRY SCHWERIN, OF BROOKLYN, NEW YORK.

DESIGN FOR FOOTWEAR.

60,708.

Specification for Design. Patented Mar. 21, 1922.

Application filed July 23, 1921. Serial No. 487,196. Term of patent 3½ years.

To all whom it may concern:

Be it known that I, HARRY SCHWERIN, a citizen of the United States, residing at borough of Brooklyn, in the county of Kings, State of New York, have invented a new, original, and ornamental Design for Footwear, of which the following is a specification, reference being had to the accompanying drawing forming part thereof.

The figure is a plan view of the design applied to a portion of the vamp of a slipper or shoe, the vamp being shown flat to better display the design.

I claim:

The ornamental design for footwear as shown.

HARRY SCHWERIN.
